UNITED STATES PATENT OFFICE.

EDWARD G. GROSS, OF COLUMBUS, GEORGIA.

CAR JACKING-FRAME.

1,251,015.

Specification of Letters Patent. Patented Dec. 25, 1917.

Application filed March 27, 1916. Serial No. 88,841.

To all whom it may concern:

Be it known that I, EDWARD G. GROSS, a citizen of United States, residing at Columbus, in the county of Muscogee and State of Georgia, have invented a certain new and useful Improvement in Car Jacking-Frames, of which the following is a full, clear, concise, and exact description, reference being had to the accompanying drawings, forming 10 a part of this specification.

This invention relates to improvements in car jacking frames.

The object of the invention is to provide a jacking frame suitable for straightening 15 the underframes and superstructures of steel cars that have become distorted in service and without the necessity of taking the cars apart, thereby eliminating unnecessary labor and avoiding the difficulties heretofore experienced in re-fitting the parts.

The invention, furthermore, consists in the improvements in the parts and devices and in the novel combinations of the parts and devices, herein shown, described and 25 claimed.

In the drawings forming a part of this specification, Figure 1 is a side elevation of a car jacking frame showing my improvements in connection therewith. Fig. 2 is 30 a top plan of the structure illustrated in Fig. 1 with one corner post in section. Fig. 3 is a transverse, vertical, section of the structure illustrated in Figs. 1 and 2, only one thrust member C being shown, the thrust member E being indicated by dotted lines, and Fig. 4 is a detailed view illustrating one of the jacks employed.

In said drawing, the frame work is shown as composed of four vertical corner posts 40 A—A, four intermediate posts B—B, two on each side of the frame work near the center thereof, transversely extending channels 10—10 which connect the vertical posts near the bottom thereof and substantially at 45 the ground level, transversely extending upper channels 11—11 connecting the tops of the posts, and diagonal bracing angles 12—12 between the two sets of four corner posts and intermediate posts as illustrated 50 most clearly in Fig. 2. Each of the posts A and B preferably comprises a pair of channels connected by plates to form columns in a well known manner. It will also be understood that suitable gusset plates 13—13 are 55 employed on the top of the frame work to provide means for connecting the diagonal

angles 12 with the other members of the frame work. At their lower ends, the posts A and B are embedded in a bed of concrete or other suitable body of masonry 14 which extends beyond the ends of the frame work as clearly appears from Fig. 1, and which has its sides extended as indicated in Fig. 3 outwardly beyond the sides of the frame work and arranged to be partly covered over 60 with earth to thereby render the frame work more stable against tipping or tilting. The vertical posts are also connected at their bottom ends by suitable channels 114 which extend longitudinally of the frame work 65 and are embedded in the masonry. The size of the frame work is made such that a box car may be run therewithin and for this purpose rails 15—15 are provided suitably mounted on ties 16 and in the top of 70 upwardly extending portions 17—17 of the masonry bed. Each of the vertical posts A and B is furthermore strengthened against bending by gussets 18—18 secured thereto near their bottom portions, said gussets 18 75 being in turn secured to transversely extending channels 10 and partly embedded in 80 the concrete or masonry.

Within the frame work, and on each side thereof, is provided a longitudinally extending, horizontal thrust member C (see Fig. 3). Each of the thrust members C preferably comprises a pair of channels 19—19 having the flanges oppositely extended and connected by suitable spacers 20 85 and eye bolts 21. Each of the thrust members C is made long enough so that it extends from one end post A to the nearest center post B, as clearly appears in Fig. 1. The thrust members C bear against the corresponding posts A and B and are vertically adjustable by means of tackles 22 suitably supported from eye bolts 23 fastened to the top members of the frame work. The ropes from each of the tackles may be operated 90 by any suitable winding mechanism and it will be understood that said tackles are detachably connected with the eye bolts 23 and 21. The thrust members C are adapted to support the jacks D in a horizontal position, 100 each of the jacks D being provided for this purpose with a hook-shaped clip 24 at its base, the hooks 24 being arranged to hang upon the inner flange of the upper channel of each member C. For convenience, each 105 of the jacks D may be provided with a perforated ear 25 adapted to receive a hook 26 110

secured to a block 27 of a tackle arrangement supported from a roller bracket 28, the roller brackets 28 being supported on a longitudinally extending track 29 mounted 5 on brackets 30 secured to the posts A and B, the tracks 29 being located near the top of the frame work and extending preferably the entire length of the frame work so that the jacks may be readily shifted to any desired point. The method of locating the jacks when employed with the side thrust member C is clearly indicated in Fig. 3.

The intermediate posts B—B on each side of the frame work are spaced an appreciable 10 distance apart as clearly indicated in Fig. 1 and secured to the inner face of each of said posts B, is a vertically extending I 15 beam 31, said I beams 31 being spaced apart as clearly appears from Fig. 1 and forming 20 a vertical guideway for a vertically adjustable, transversely extending thrust member E. The thrust member E is preferably of the same design as the thrust members C, that is, it comprises a pair of channels 25 rigidly connected and has the flanges of the channels adapted to coöperate with the hooks on the jacks D. The transverse thrust member E may also be lifted and lowered by suitable tackles as will be understood. 30 The transverse member E is normally located flush with the top of the central portion of the masonry bed and is provided on its top with short rail sections 32—32 adapted to aline with the rails 15 and make the 35 latter continuous. In order to lessen expense and minimize the number of parts, the side thrust members C are adapted to be shifted from one end of the frame work to the other and to facilitate this operation, 40 a longitudinally arranged series of horizontal rollers 33 are provided on each side of the frame work on which the members C are adapted to be supported while being shifted from one end of the frame work to 45 the other.

In order to lift the car bodies and to separate the same from the trucks, I preferably provide four tackle arrangements 34 located near the corners of the frame work 50 and suitably supported from eye bolts 35 attached to the upper members of the frame work. For operating the tackles, I provide four winches F—F to which the pulley ropes are run. Each of the winches F is secured 55 to a vertical post at a convenient height for the operator and preferably overlaps the connection between the top of the corresponding gusset 18 and vertical post. Each winch F preferably comprises a pair of 60 castings 36 having suitable bearings 37 and 38 for the journals of a winding drum 39 and gear shaft 40. The gear shaft 40 is operated by a lever 41, said shaft 40 having a small gear wheel 42 thereon which meshes 65 with a larger gear wheel 43 secured to the

shaft of the winding drum 39. A locking pawl 44 is pivotally mounted between the plates 36 and coöperates with a ratchet wheel 45 secured to the shaft 40, to thereby lock the parts in any desired position.

70

At suitable points, a plurality of rings 46 are provided, the same being retained in fixed position by means of eye bolts 47 embedded in the concrete.

The method of using the jacking frame 75 is as follows: To straighten the underframe of a car which has been bowed laterally, the thrust members C—C are elevated to the proper position and jacks applied thereto, two jacks being employed on one side of the 80 car and a third jack on the opposite side of the car which is arranged to engage the car at the center of the bowed or outwardly bent portion. The last named jack is then operated to apply pressure to the side of the 85 car, it being understood that the pressure transmitted to the thrust members C will be taken up by the vertical posts A and B. It will also be obvious that the superstructure of the car can be straightened in the 90 same manner as the underframe by elevating the members C to the proper height and applying the jacks in the same manner. When it is desired to straighten the end of a car, the car is run half way out of the frame 95 work so that the transversely extending thrust member E may be elevated to the proper position and the jacks attached thereto and pressure applied to the end of the car. In this operation, it is necessary 100 that the car be held from longitudinal movement and for this purpose chains are employed which are fastened to any suitable portion of the car, the ends of the chains being attached to the rings 46—46. The 105 ends of the super-structure may be similarly straightened as will be apparent. In the event that the underframe of the car is buckled upwardly, chains are passed over the car at the center and attached to said 110 rings 46. The jacks are then used to apply pressure vertically to the ends of the car to thus strengthen the underframe. In the event that the underframe sags at the center, that is, is buckled downwardly, securing 115 chains are passed over the ends of the car and pressure applied by the jacks at the center of the car.

From the preceding description, it will be seen that the car jacking frame which I 120 have provided is of relatively simple construction; may be readily fabricated; is provided with means for straightening the car in any desired direction; and is provided with means permitting easy and convenient handling of the various parts.

Although I have herein shown and described in detail what I now consider the preferred embodiment of my own invention, the same is merely illustrative and I con- 125 130

template all changes and modifications that come within the scope of the claims appended hereto.

I claim:

5 1. In a car jacking frame, the combination with a rigid frame work within which a car is adapted to be received, of vertically adjustable side thrust members located between the car and the sides of the frame work and against which jacks are adapted to be placed to thereby exert transverse pressure on the car.

10 2. In a car jacking frame, the combination with a rigid frame work within which a car to be operated upon is adapted to be placed, of a vertically adjustable, horizontal thrust member on each side of said frame work, said thrust members being so arranged as to have jacks bear thereagainst to thereby exert lateral pressure against the car.

15 3. In a car jacking frame, the combination with a frame work, of a transversely extending thrust member, adjustable vertically, associated with said frame work, said thrust member being adapted to have jacks bear thereagainst whereby pressure may be exerted longitudinally of a car on its end.

20 4. In a car jacking frame, the combination with a frame work, of a transversely extending thrust member, adjustable vertically, associated with said frame work, said thrust member being adapted to have jacks bear thereagainst whereby pressure may be exerted longitudinally of a car on its end, and means by which a car may be tied to the frame work and thereby prevented from longitudinal movement while being operated upon.

25 5. In a car jacking frame, the combination with a rigid framework within which a car is adapted to be received, of side thrust members located on the interior of said framework and adapted to be in position between the car and the sides of said framework, said side thrust members being movable to different positions and adapted to have pressure exerted transversely thereagainst, and means associated with said framework to facilitate moving said thrust members from one position to another.

30 6. In a car jacking frame, the combination with a rigid frame work within which the car to be operated upon is adapted to be received, of vertically adjustable, longitudinally arranged side thrust members, and a vertically adjustable, transversely extending thrust member.

35 7. In a car jacking frame, the combination with a rigid frame work within which the car to be operated upon is adapted to be received, of means associated with said frame work against which jacks are adapted to exert pressure when operating on the car, and trolley tracks mounted on the interior of said frame work, said tracks being ar-

ranged to support the jacks and permit the latter to be adjusted relatively to the frame work.

8. In a device of the character described, the combination with a rigid frame work 70 adapted to receive a car therewithin, of a transversely extending, vertically adjustable thrust member located substantially at the center of said frame work, said member being vertically slideable between two upright 75 members on each side of said frame work.

9. In a car jacking frame, the combination with a rigid frame work, of a longitudinally extending, vertically adjustable thrust member at the side of said frame work, said 80 member approximating half the length of the frame work, said member being shiftable longitudinally of the frame work and adapted to be used at either end thereof.

10. In a car jacking frame, the combination with a rigid frame work, of a longitudinally extending, vertically adjustable thrust member at the side of said frame work, said member approximating half the length of the frame work, said member being shiftable 90 longitudinally of the frame work and adapted to be used at either end thereof, and a series of rollers arranged longitudinally of the frame work at the bottom thereof and over which said member is adapted to ride 95 while being shifted from one end of the frame work to the other.

11. In a car jacking frame, the combination with a frame work comprising vertical corner posts and two vertical posts on each 100 side of the frame work near the center thereof, and braces connecting said posts at the top, of a transversely extending thrust member at the center of said frame work, said member being slidably mounted between 105 said posts at the center of the frame work at the sides thereof, pressure from said member being transmitted to said vertical posts.

12. In a car jacking frame, the combination with a rigid frame work comprising 110 vertical posts embedded in masonry at their lower ends and connected and braced at their upper ends, of longitudinally extending, vertically adjustable thrust members along the inner sides of said frame work, a transversely extending, vertically adjustable thrust member, tackles for adjusting said members vertically, and winches for operating said tackles.

13. In a car jacking frame, the combination with a rigid frame work and rails extending longitudinally of the frame work 120 arranged to permit a car to be moved therewithin, of a transversely extending thrust member associated with said frame work 125 and movable into and out of operative position, said thrust member being adapted to resist pressure exerted therebetween and the end of a car applied longitudinally of the car.

14. In a car jacking frame, the combination with a rigid frame work provided with a bed of masonry at the bottom thereof, and rails extending longitudinally of said frame work arranged to permit a car to be moved within said frame work, of longitudinally arranged thrust members on the inner sides of the frame work, a transversely extending thrust member located substantially at the center of the frame work, means embedded in said masonry to which chains may be attached for securing a car against longitudi-

nal or upward movement while being operated upon, and means associated with said frame work by which a plurality of jacks 15 may be easily handled.

In witness that I claim the foregoing I have hereunto subscribed my name this 14th day of March 1916.

EDWARD G. GROSS.
